UNITED STATES PATENT OFFICE

ROBERT E. MANLEY, OF YORK, PENNSYLVANIA, ASSIGNOR TO MANLEY MANUFACTURING COMPANY, OF YORK, PENNSYLVANIA, A CORPORATION OF DELAWARE

LEVER MECHANISM

Application filed October 15, 1926. Serial No. 141,850.

This invention relates to screw presses and has for its object the provision of a simple and efficient quick detachable auxiliary lever mechanism whereby powerful pressure can be secured to start relative movement between two pieces.

A further object of the invention consists in the provision of a locking device between a horizontal rod and a vertical shaft pivoted thereto. A still further object of the present invention consists in the provision of a counterbalanced pawl and ratchet advancing mechanism for a screw, capable of movement in a plurality of ways to accomplish variety 15 of speeds giving inverse power.

In the relatively heavy presses, for example, those used in garages, these varying from three to fifty tons or more, the time allotted a definite piece of work will not permit 20 the exclusive use of the very slow speed of a high leverage. It is quite customary to provide a small rack and pinion arbor press to one side of the main frame to take care of small work, this being an auxiliary to the 25 central screw which may be adjusted to position by spinning freely and which may then be moved by a long rod leverage having an option as to the number of teeth the pawl shall slip over but having no other provision 30 for slow speed high leverage work.

In the device illustrated in the drawings a very simple form of screw press is illustrated wherein all of the advantages of previous types of the same general nature are 35 maintained and yet a very simple and highly efficient higher leverage is provided for the frequently occurring need for extreme power for a very brief time, as for example, to enable the mechanic to start a bushing or gear, the 40 movement naturally being continued immediately under very much faster leverage as for example by use of the rack and pinion.

In the drawings:—

Figure 1 is a side elevation of a press embodying the present invention.

Figure 2 is a plan view of the leverage.

Figure 3 is an elevation.

Figure 4 is a perspective view of a portion of the leverage shown in Figure 3.

The frame of the press is made up of two

multi-piece standards 10 each supported at the bottom by a base 11, these bases being tied together by the straps 14 in the usual manner. The side bars of the uprights continue the entire height of the press and are secured at their tops to the channel pieces 15 which support the screw press mechanism 20. The table 21 is slidably mounted on the uprights 10 and may be pinned to them at the desired height depending upon the class of 55 work being operated upon.

The ratchet wheel 25 is of old and well known construction as is the screw proper which is numbered 26 in the drawings. Mounted for rotation with respect to the 55 wheel is a pawl carrying arm 30 having at its far end a counter weight 31 which exactly balances the front end which carries the pawl and also the usual socket 34 to receive a handle or rod 36 which need have no positive 70 connection with the socket. Extending laterally from the forward end of the pawl carrying arm 30 and on the opposite side from the socket 34 are two integral pierced lugs 38 receiving loosely between them a bar 40 75 which is secured by and pivoted upon the pin 42 conveniently held in the lugs or ears 38 merely by gravity.

Mounted in two brackets 44 and 45 secured to the near left hand standard 46 (which is 80 part of the upright 10) is a vertical shaft 50 carrying at its top a lever arm 51 perforated in a plurality of places as at 52 and 53 and having a ledge 56 which slightly overhangs all of the holes. The vertical shaft 50 is 85 oscillated by a collar 58 having a socket 59 to receive the handle 36. Socket 59 and lever arm 51 form with the vertical shaft 50 a bell crank lever, the arms of which may be parallel, but it is somewhat more convenient 90 to make the angle between them from ten to twenty degrees so that the arm 51 is slightly nearer the axis of the screw when this super-leverage is in use.

A slide 60 is freely movable on the bar 40 95 but may be held in adjusted position by a set screw 61. This slide carries a locking member 62 to lock the bar 40 to the lever arm 51, this being accomplished in the following manner: The slide is pushed toward the screw 100

and the downwardly directed circular projection 64 on the rod is inserted in one of the holes in the lever arm, 52 for the greatest power, 53 for the somewhat less power and the hole in between for an intermediate leverage and power. With the projection 64 in the selected hole the slide 60 is moved until the locking member 62 is beneath the ledge 56 at which time the thumb screw 61 is tightened slightly, absolutely preventing removal of the parts.

We will assume that a very heavy piece of work is to be operated upon requiring the greatest possible power. The projection 64 on the bar 40 is dropped into its pivoting hole 52 and the parts locked into such position by the slide 60. The pin 42 is inserted to connect the auxiliary or vertical shaft 50 with the pawl carrying arm 30. The lever or handle 36 is in the socket 59 which is considerably lower than the pawl and is at a height to be most convenient to the operator who grasps the rod or lever 36 with one hand and with the other hand holds and supports the work under the screw. This method of operating permits the mechanic to exert muscular action in a more efficient way than with vertical leverage and hence the leverage developed will be greater. When the work is started the pin 42 is slipped out, and the bar 40 thrown to the left, and the lever handle 36 shifted from socket 59 to socket 34 at which time the action continues as a simple pawl and ratchet movement quite similar to that well known and old except for the fact that the pawl carrying arm is counterweighted, this latter it is believed, being new in this art.

What I claim is:—

1. In a press, a screw, a member for advancing the screw, a vertical shaft, a pair of arms on said vertical shaft forming with it a bell crank lever, quick detachable means for connecting the screw advancing means and one arm of the bell crank lever so that oscillation of the vertical shaft advances the screw, and means permitting the ready securing and releasing of the connection between said screw advancing means and lever arm.

2. In a screw press, a screw, a wheel for advancing said screw, counterbalanced means pivoted coaxial with the screw for rotating said wheel, a vertical shaft pivoted to one side of said screw, a pair of substantially parallel arms carried by said vertical shaft, one of said arms being a manually operated lever and the other arm being perforated in a plurality of places, a bar having pivotal connection with any one of said perforations and readily detachable means for pivotally connecting said bar to said wheel rotating means.

3. In a press, a screw, a ratchet wheel having threaded engagement with said screw for advancing same, an arm pivoted concentric

with said screw and wheel and carrying a wheel engaging pawl, and a counterweight balancing the pawl carrying end of said arm whereby the wheel can be conveniently spun with the pawl.

4. In a device of the character described, a lever having an overhanging ledge, a bar having a pin and socket connection with said lever, and means freely slideable along said bar and under said overhanging ledge to lock the pin in its socket.

5. In a device of the character described, a vertical shaft, a pivoting support therefor, a pair of horizontal arms carried by said shaft, a bar, a pin and socket connection between said bar and one of said arms, and means for locking said pin in said socket.

6. In a device of the character described, an interconnected lever and bar quickly detachable from each other, the said lever being provided with a plurality of apertures adapted to receive the bar, the said lever being also provided with a ledge overhanging the said apertures, and a wedge slideably carried by the bar and adapted to engage the said ledge and bar to secure the contact between the lever and bar.

7. In a device of the character described, a lever movable about a fixed pivot, a bar, quick detachable means for pivoting the bar to the lever whereby rotation of the lever about its pivot will transmit power in the direction of the length of the bar, and means slideable on the bar to prevent movement of the pivoted end of the bar in a direction parallel to the pivotal axis of the lever.

8. In combination, a pawl and ratchet mechanism, a lever, a link pivoted to the lever and to the pawl and ratchet mechanism, and means slideable along the link to permit and to prevent disassociation of the link and the lever.

9. In combination, an arm pivoted about a vertical axis and having a plurality of holes therein at varying distances from the axis, a bar having a downturned portion to snugly and pivotally engage any one of said holes, and means carried in part by the arm and in part by the bar to prevent accidental removal of the downturned portion when the bar and lever are in chosen adjusted position.

10. In a press, a screw, a wheel for moving the screw to and from the work, a pawl and ratchet mechanism for turning the wheel step by step, a counterbalance for a portion of said mechanism, means for rapidly disconnecting by hand a portion of said pawl and ratchet mechanism, whereby the wheel may be rotated by hand to carry with it the counterbalanced portion of the pawl and ratchet mechanism so as to advance or retract the screw with rapid motion.

In testimony whereof I affix my signature.

ROBERT E. MANLEY. 130
